UNITED STATES PATENT OFFICE.

ERNEST D. FOSTER, OF LOS ANGELES, CALIFORNIA, ASSIGNOR, BY MESNE ASSIGNMENTS, TO UNITED AIR SPRING COMPANY OF ARIZONA, A CORPORATION.

PNEUMATIC SPRING.

1,242,431.

Specification of Letters Patent.

Patented Oct. 9, 1917.

Application filed August 18, 1914. Serial No. 857,375.

To all whom it may concern:

Be it known that I, ERNEST D. FOSTER, citizen of the United States, residing at Los Angeles, in the county of Los Angeles, and 5 State of California, have invented certain new and useful Improvements in Pneumatic Springs, of which the following is a specification.

My invention relates to an improvement in 10 pneumatic springs, and more particularly to such springs as are intended to be used upon vehicles to relieve the shock to the rider.

The object of this invention is to provide 15 a pneumatic spring in which the structure is substantial, readily attached, and when attached, gives a highly efficient cushioning action without a noticeable rebound.

This invention relates to certain other 20 novel features of construction and combinations of parts which will be hereinafter fully described and pointed out in the claims.

In the accompanying drawings:

Figure 1 is a vertical sectional view to 25 show one form which the invention may take, and

Fig. 2 is a similar view to show a slightly modified form.

A top-plate A is flanged at its edge as at 1 to form a face groove, and a flexible casing B is secured in this groove by means of 30 a collar 2, which is held in place by bolts 3, 3. The casing B is made semispherical or conoid in form, and is preferably of fabric reinforced rubber. A lining plate 4 is preferably received within the top plate A, and has a flange on the edge thereof which fits tight against the casing B.

A stem C is bifurcated to fit over the part 40 of the member to which the spring is to be attached in its lower part, and a bolt 6 is passed from the inside of the casing B through an opening in this casing, and is screwed into the stem C.

It is preferable that this connection 45 between the stem C and the casing B be formed to be fluid-tight. The bolt 6 has a passage 7 therethrough, in which the upper threaded end of a nipple 9 is screwed, the latter forming a continuation of the bolt. An air tank 50 D is provided with an opening 11 through which it may be filled, and a pipe or hose-line 12 extends from this tank D to the nipple 9. A bolt 13 is secured to the upper plate A in such a relation that it forms a

means of attachment for the spring at that 55 end.

In use the spring would be connected in position, the tank is then filled with air at any suitable pressure as the circumstances may require. The air flows through the tube 12, and fills the casing B which supports the weight. As an obstruction is encountered, or a shock is transmitted to the spring, the stem C is brought nearer to the top plate A, and the casing B is deformed, decreasing its 60 cubic area and causing a part of the air to be displaced therefrom, and forced back through the tube 12 to the air tank D. This relieves any extraordinary compression in the casing B, and as the air forced therefrom mingles with the total volume in the air tank, there is no perceptible compression and hence no force to re-act and no recoil. When the abnormal load is removed and the blow is spent against the increased area, the 70 cushion will reform at practically the same pressure, and consequently the same air-cushion effect will be maintained on the reshaping of the casing, as on its deformation.

In the form shown in Fig. 2, the parts are 80 identical with the exception that the stem C' and the parts connected therewith are so modified that a fluid-tight connection is formed at that end, and a tube 14 is connected through the top-plate A'. With this 85 structure, the same result is accomplished in the same manner.

From the foregoing, it will be seen that I have provided a device in which a very efficient result is obtained, and one which is 90 cheaply manufactured, and readily applied to take the place of the ordinary metal spring now in general use.

It will be seen that slight changes might be resorted to in the form and arrangement 95 of the several parts described without departure from the spirit and scope of the invention, and hence I do not wish to limit myself to the exact construction herein set forth, but:

I claim:

1. A pneumatic spring comprising a flexible casing having an annular flange at the upper edge thereof, a top plate having a flanged edge adapted to receive the flanged edge of the flexible casing, a collar having an upturned flange adapted to fit within the flange of the top plate and embrace the un-

derside of the annular flange of the flexible casing, and an internal disk having a downwardly projecting flange which forms an internal lateral support for the flexible casing, 5 and means for drawing the collar and the top plate toward each other in an air-tight embrace of the opposite faces of the interposed flange of the flexible casing.

2. A pneumatic spring comprising a flexible casing having an annular flange at the upper edge thereof, a top plate having a flanged edge adapted to receive the flanged edge of the flexible casing, a collar having an upturned flange adapted to fit within the 15 flange and embrace the under-side of the annular flange of the flexible casing, means for

drawing the collar and top plate toward each other in an air-tight embrace upon the opposite faces of the interposed flange of the flexible casing, a stem, a hollow bolt extending through the flexible casing into the stem, nuts on the bolt for securing the flexible casing to the stem, an air-tank and hose extending from the air-tank to the hollow bolt, whereby connection is established between 20 the flexible casing and the air-tank.

In testimony whereof I affix my signature, in the presence of two witnesses.

ERNEST D. FOSTER.
